UNITED STATES PATENT OFFICE.

CHARLES L. S. TINGLEY, OF ST. DAVIDS, PENNSYLVANIA.

RAILWAY TICKET.

Application filed May 18, 1922. Serial No. 561,811.

To all whom it may concern:

Be it known that I, CHARLES L. S. TINGLEY, a citizen of the United States, and a resident of St. Davids, county of Delaware, 5 and State of Pennsylvania, have invented certain new and useful Improvements in Railway Tickets, of which the following is a specification, reference being had to the accompanying drawing.

10 My invention relates to improvements in railway tickets particularly adapted for use in commutation travel.

A principal object of my invention is to provide tickets for use in railway travel by 15 which travel will be stimulated.

A further object of my invention is to provide a railway ticket in the use of which the rates of fare automatically decrease in proportion to the increase in travel.

20 A further object of my invention is to provide a railway ticket comprising separate and detachable zone coupons or tickets and which may be used interchangeably in the different zones for which the ticket is 25 issued.

A further object of my invention is to provide a single form of railway ticket provided with zone coupons particularly adapted for monthly commutation travel on a 30 railway line which is divided into zones, a passenger being enabled thereby to purchase any desired number of the zone coupons and making it unnecessary for the railway company to provide separate tickets for each 35 individual zone.

A further object of my invention is to provide a railway commutation ticket of the type described having an auditor's stub separable from the ticket at the time of sale 40 whereby quick and accurate auditing is assisted.

45 My invention further includes all of the other various novel objects and features of construction and arrangement hereinafter more definitely specified and described.

In the drawings, Fig. 1 is a top plan view of the ticket; Fig. 2 is a perspective view; Fig. 3 is a perspective view of the passenger's end of the ticket with some of the 50 leaves raised and Fig. 4 is a perspective view of the auditor's end of the ticket. Like letters designate the same parts in the different figures.

55 The ticket A is composed of a number of leaves B, for example one hundred, which are securely joined together at each end in

any suitable manner, as by staples C. At the left hand side of the ticket are printed the conditions of sale of the ticket, a line D being provided for the name of the purchaser and a line E for his signature in acceptance of the conditions.

The ticket illustrated in the drawings is adapted for use on a railway line which is divided into seven zones, a coupon being 60 provided for each of the zones, the division lines between the zone coupons being preferably perforated thereby assisting in the detaching of the zone coupons. It will be understood, of course, that my improved 65 ticket is adaptable for use on a railway line of any number of zones, the embodiment shown and described being illustrative only. At the right hand end of the ticket is the auditor's stub which bears the same serial 70 number, in this instance "No. 000", as the passenger's end of the ticket, and, as will be seen, the year, in this instance "1922", is printed upon both the passenger's stub and the auditor's stub the number "1" appearing 75 on the passenger's stub indicating the first month of the year, i. e., January, which appears in abbreviated form on the auditor's stub.

To illustrate the use of the ticket we will 80 assume that a commuter lives in zone No. 4 and commutes daily into zone No. 1, that is, through four zones. He purchases his commutation ticket on the first day of the month, asking for a four zone ticket and paying 85 therefor the sum of \$6.00 as indicated on the zone coupon for zone No. 4. The ticket agent severs the entire ticket on the line F between zone coupons 4 and 5 in any suitable manner, delivering the passenger's end 90 to him and forwarding the auditor's stub and zone coupons for zones 5, 6 and 7 integral therewith to the auditor who is thereby informed that ticket No. 000 has been 95 sold to a commuter living in the fourth zone who has paid therefor the sum of \$6.00, which sum, for purposes of convenience, is 100 also printed on zone coupon No. 5 as shown.

The purchaser of the ticket, in accordance 105 with the conditions of sale printed on the ticket and which have been accepted by the purchaser, on entering any zone pays the conductor the sum of five cents at the same time exhibiting to him the commutation ticket whereupon the conductor will either 110 punch or preferably detach one of the zone coupons.

The ticket is sold at a figure which will make the cost of travel to the passenger less than if he paid the usual cash rates during each trip. For example, assuming that the 5 commuter lives in the fourth zone and makes thirty round trips per month, paying cash each trip at the rate of ten cents per zone, the cost to him per day would be eighty cents or \$24.00 per month. If, however, he 10 purchases the commutation ticket the cost to him would be forty cents per day or \$12.00 per month cash paid at the time of travel and in addition thereto the sum of \$6.00 paid for the ticket for four zones 15 making the total cost to him of his monthly commutation travel \$18.00 and resulting in a saving of \$6.00.

If, as suggested above, the ticket comprises one hundred leaves, then the 20 purchaser living in the fourth zone would by the payment of \$6.00 secure four hundred zone coupons, and in commuting thirty days per month, he would use two hundred and forty zone coupons which would be at the 25 rate of two and one-half cents per zone, resulting in a saving of two and one-half cents per zone, through the use of this ticket; if, however, a commuter only uses two hundred of the zone tickets for which 30 he would have paid the like sum of \$6.00, the cost of the ticket would be at the rate of three cents per zone and if he used all of the zone tickets, viz: four hundred, the cost 35 of the ticket would be at the rate of one and one-half cents only per zone.

It will therefore be seen that there is an automatic decrease in fare in proportion to the greater extent of travel which, as has been demonstrated practically, will stimulate 40 travel and increase the number of cash five cent fares payable by the holder of the ticket per each zone, and result in a substantial increase in cash income to the railway companies utilizing my improved ticket.

45 It is not necessary that the conditions of sale be printed other than on the top leaf and the corresponding space in the other leaves may be utilized, if desired, for advertising purposes, and the advertising rights

sold by the railway company with a consequent increase of income. 50

While I have herein described one embodiment of my invention, I do not thereby desire or intend to limit myself to the precise arrangement shown and described as 55 the same may be modified and varied in minor particulars without departing from the spirit and scope of the invention as defined in the appended claims.

Having thus described my invention, I 60 claim and desire to protect by Letters Patent of the United States:

1. A railway ticket for commutation travel comprising a plurality of leaves secured together at each end, said leaves comprising a plurality of zone coupons disposed between the ends of each leaf, an appropriately designated detachable auditor's stub at one of the ends and an appropriately designated passenger's stub at the other end. 65 70

2. A railway ticket for commutation travel comprising a plurality of leaves secured together at each end, said leaves comprising a plurality of zone coupons similarly delineated and disposed between the 75 ends of each leaf, an appropriately designated detachable auditor's stub at one of the ends and an appropriately designated passenger's stub at the other end, the entire ticket being adapted to be severed into two 80 parts on any delineation. 85

3. A railway ticket for commutation travel comprising a plurality of leaves permanently secured together at each end, said leaves comprising a plurality of zone coupons similarly delineated and disposed between the ends of each leaf, an appropriately designated detachable auditor's stub at one of the ends and an appropriately designated passenger's stub at the other end, 90 said stubs each bearing the ticket number and the month of issuance, the entire ticket being adapted to be severed into two parts on any delineation. 95

In witness whereof I have hereunto set my hand this 16th day of May, 1922.

CHARLES L. S. TINGLEY.
